UNITED STATES PATENT OFFICE.

SIDNEY H. SHORT, OF CLEVELAND, OHIO, ASSIGNOR TO THE WALKER COMPANY, OF NEW JERSEY.

CONTROLLING APPARATUS FOR ELECTRIC MOTORS.

SPECIFICATION forming part of Letters Patent No. 629,399, dated July 25, 1899.

Application filed April 25, 1896. Serial No. 589,083. (No model.)

To all whom it may concern:

Be it known that I, SIDNEY H. SHORT, of Cleveland, in the county of Cuyahoga and State of Ohio, have invented a new and useful Improvement in Controlling Apparatus for Electric Motors, of which the following is a specification.

My invention relates to controlling apparatus for electric motors hereinafter fully described and claimed.

These motors may be used singly, in pairs, or any number of motors may be arranged to be controlled from the same controlling apparatus.

Where more than one motor is to be controlled they may be coupled in series, parallel, or any combination of series and parallel for the purpose of regulating the speed and power of the motors by means of the apparatus described in this specification.

The main object of this invention, aside from making various combinations with motors, is to avoid the destructive arcing usually resulting when making the changes in combinations or in cutting off the current from the motor or motors.

This controlling apparatus is more particularly intended to be used for starting and controlling the speed of electric traction-motors; but the device is equally applicable to the control of stationary motors wherever frequent starting, stopping, and changes in speed are required.

Figure 1 represents diagrammatically the arrangement of the various parts of the controller and connections to the motors which constitute the invention. Fig. 3 is a diagrammatic representation of the changes in the circuit corresponding to different positions of the controller, and Fig. 2 is a top plan view of the controller and series break.

The controller consists of two parts—namely, that part indicated generally by the letter A, which forms the combinations in the motor-circuit and cuts in and out resistances, and another part marked generally B, intended to dissipate the arc which is formed at the moment of breaking contact. The part A consists of a cylinder carrying upon it metallic contact-plates arranged to come in contact with and connect various stationary

terminals, while the part B is a separate cylinder arranged simply to make and break contact. The part B consists of a series of stationary contact-plates marked 30, 31, 32, 55 33, 34, 35, 36, and 37, each of these, except 31 and 37, being arranged in pairs, as shown in Fig. 1. The moving part carries a series of corresponding contact-plates arranged in pairs—24, 25, 26, 27, 28, and 29—the parts 24 to 28 being arranged to come in contact with the corresponding stationary contacts a little before the contacts 29 come in contact with 30 and 31 and to break a little later than contact 29 when turned in the reverse direction. 60 The contacts 31 and 37 are connected by a conductor V, 30 is connected to the trolley, and 37 is connected by line 13 with the motor-circuit.

M M' represent two motors, and R R' represent two resistance-coils.

S, S', and S" represent cut-out switches by which either of the motors may be cut out of circuit.

The main controlling-switch A has on it a series of contact-plates a, b, c, d, e, l, g, h, i, j, and k, which are connected, as shown, and it also has a series of other contact-plates t, u, w, x, z, and y, (shown in black,) which are intended mainly for the purpose of dissipating the arc which forms in the controller at the time of breaking contact.

The top of the controller is provided with a ratchet-wheel D, (shown in Figs. 1 and 2,) which is moved by the handle H in either direction as the controller is moved. The top of the movable part of series break B is provided with a crank C, and a spring E is attached at one end to a pin K on said crank C and at the other end to a stationary pin N 90 in any convenient part of the controller-box, so arranged that when crank C is moved from the position shown in Fig. 2 to the left said spring will swing across the center line of crank C, and thus tend to throw said crank in 95 one direction or the other on the well-known principle of the double-acting spring-hinge.

I represents an arm which is loosely pivoted at one end to the post Z, to which controller-crank H is attached, and at its outer 100 end is connected by a link L with the end of crank-arm C.

P and P' represent two curved pawls, each pivoted on the pin J, which connects arm I with link L, and drawn together by a spring F, whose line of strain is between said pin 5 and the inner end of arm I, so that said pawls are normally always drawn toward each other.

O O' represent stationary pins on the controller-case adapted to come in contact with pawls P and P', respectively, and hold them 10 out of engagement with ratchet-wheel D.

Q represents a lug on ratchet D, adapted to strike the end of pawl P, so as to shift the pawl into the position shown in Fig. 2.

From the foregoing description it will be 15 seen that I provide an initially-acting switch having operative connection with the circuit-changing and resistance-varying switch, the arrangement being such that the first movement of the last-mentioned switch—that is, 20 the controlling-switch—in one direction—that is, in a direction toward the "on" position—operates to close the first-mentioned or initially-acting switch and that said initially-acting switch is maintained in closed position 25 during the entire "on" movement of the controlling-switch, and hence during the circuit changes and resistance variations in the motor-circuit. It will also be seen that the first movement of the controlling-switch in the 30 opposite direction—that is, toward "off" position—operates to open the initially-acting switch and that said initially-acting switch remains in open position during the entire "off" movement of the controlling-switch. 35 It is evident that this generic idea may be embodied in many specifically different constructions. While, therefore, one form of embodiment is shown in the accompanying drawings, I desire it to be understood that 40 the invention is not limited or confined to the specific construction shown. For instance, the construction and arrangement of the controlling-switch or of the initially-acting switch or of the connections between the two 45 may be widely varied and altered without departure from the spirit and scope of the invention.

The operation of this invention is as follows: Assuming the parts to be in the position shown diagrammatically in Fig. 1, if controller A be moved so as to bring it into the position shown in Fig. 2, the lug Q strikes the end of pawl P, forces it out, thus moving arm I, link L, and drawing crank-arm C until by means of spring E it is drawn into the position shown in Fig. 2. This brings the contacts 24 to 29 into contact with the corresponding contacts 30 to 37, and the line of least resistance from the trolley T is as follows: 30 to 29 to 31 through line V, thence through line 13, resistance R R', line 18, motor M, line 20, contact-finger 11, contact j, contact i, contact-finger 8, line 21, motor M' to ground, both resistances and both motors 60 being in series. During any further movement of controller A to the left to vary the resistance of the motor-circuit either by cut-

ting in or out resistances or by varying the coupling of the motors the ratchet D runs idly over the end of pawl P' without affecting the 70 series break B. If now the handle H be turned to the right, Fig. 2, for the purpose of cutting off current from the motors, the ratchet-wheel D actuates pawl P', and through said pawl swings link L and crank-arm C until spring 75 E passes over the center line of the crank-arm C, when said spring opens the series break with great rapidity, thus cutting off the entire current from the motor-circuit and dissipating the resulting spark between the segments 24 to 37, which are cut into circuit as 80 soon as contact 29 leaves contacts 30 and 31. This change of position throws pawl P' out and away from ratchet-wheel D through pin O', and spring F brings pawl P into position 85 to be struck by lug Q when the controller is again moved. It is evident that when the series breaks are all closed the path of current will be from the lower contact-finger 30, through contacts 29 to 31, thence by wire V 90 to 37, and that in reversing this operation contact 31 is first cut out, thereby cutting out wire V and forcing the current to pass through contacts 24 to 37. The operation above described of closing the circuits has 95 thrown the two motors and resistances in series, as shown in position first of Fig. 3. A further movement of controller A brings contacts b and c against fingers 2 and 3, thus cutting out resistance R and putting the parts 100 in the second position shown in Fig. 3. A still further movement of controller A brings contact d in connection with finger 4, thus cutting out both resistances, as shown in the third position, Fig. 3. The next operation of 105 the controller is to couple the motors in multiple. In doing this the resistance of the circuit would be decreased to one-quarter of the resistance of the third position, Fig. 3, and this would make too sudden an increase in 110 speed; so it is advisable for the purpose of preventing a violent forward plunge of the car to bring back one resistance into the circuit. Therefore the next movement of the 115 switch A to the left brings segment a in contact with finger 1, thus permanently short-circuiting resistance R. It also brings the shaded contacts t and u in contact with fingers 5, 6, and 7 and shaded contact x in contact 120 with fingers 9 and 10, thus forcing the current 120 after it leaves finger 2 to pass to t, to 5, to 9, to X, to 10, to 7, to u, to 6, and on through the motors by way of line 20, finger 11, contact j, finger 8, line 21. A further slight movement of switch A will break all these 125 contacts open, and the arc, which would otherwise have been formed between d and 4, is broken into five small sparks in series which are not destructive in their action on the contacts. This breaking open of five contacts 130 around the resistance R' is illustrated at X in position n, Fig. 3. The motors are now running in series with one resistance in circuit. The next movement of the controller

A to the left brings the shaded contacts *w*, *z*, and *y* in contact with the fingers 5, 7, 8, 9, and 10 and also brings contact *k* in contact with finger 12, and by this time segment *i* has 5 left finger 8. The circuit at this time is as shown in position *o*, Fig. 3, motor *M'* being short-circuited by the direct connection of line 15 to ground through segments *j* and *k* and finger 12. The next movement of the controller *A* to the left breaks the segments from 10 their respective fingers in series, and the self-induction spark of motor *M'* is broken up into five parts and rendered harmless, and this brings the parts in the position shown at *p*, 15 Fig. 3, the breaking being represented at *X*. These three steps are in practice passed over rapidly in order to get to the next position, marked 4 in Fig. 3, in which the two motors 20 are in multiple with one resistance *R'* in circuit. A further motion of the switch *A* short-circuits resistance *R'* by means of contact *l*, and the parts are in the fifth position, Fig. 3, 25 the two motors in multiple without any resistance in the circuit. On moving switch *A* toward the "off" position the series break *B* is immediately opened, as above described, and the circuit closed at that point, the resulting arc being distributed among all the contacts 24 28 32 37, thus rendering the spark 30 harmless, and this effect is indicated at *X* in the "off" position, Fig. 3, and the controller may be returned to its starting-point without any current passing through the system and therefore without sparking. To cut out motor *M*, 35 switches *S* and *S'* are opened, in which case motor *M'* will run on the lower half of the switch *A* with both resistances or only one resistance or none in circuit, and by opening switches *S'* and *S''* motor *M'* is cut out and 40 motor *M* can be operated with both resistances, with one resistance, or with no resistance in circuit.

What I claim as my invention, and desire to secure by Letters Patent, is—

45 1. In combination with a motor-circuit and a controlling-switch for said circuit, a series break consisting of a series of stationary contact-points, a series of movable contact-points, a device normally having operative engagement with a movable part of the controlling-switch when the latter moves toward the "on" position, means for automatically disestablishing said engagement upon reaching the "on" position, a connection between said device and the movable contacts of the series break, and a separate device attached to said connection and having operative engagement with said movable part of the controlling-switch when the latter is moved toward the 50 "off" position, whereby the first movement of the controlling-switch toward the "on" position throws the contact-points of the series break into circuit and leaves them in that position during any further movement in the 55 60 65 same direction of the controlling-switch, while any movement of the latter toward the "off"

position at once opens said contact-points, substantially as described.

2. The combination with a motor-circuit and controlling-switch for said circuit, of a 70 series of stationary contact-points, a series of movable contact-points, a spring for throwing said movable contact-points quickly in or out of contact with said stationary points when moved, and a connection between said movable contact-points and said controlling-switch whereby said controlling-switch is capable of throwing said movable contact-points in contact with said stationary contact-points when moved in one direction and of breaking 80 contact between said two points when moved in the opposite direction, substantially as and for the purposes set forth.

3. In combination with a switch adapted to control a motor-circuit, a spring-switch having 85 a number of stationary and a corresponding number of movable contact-points adapted to close or open the circuit controlled by the controlling-switch, a device normally having operative engagement with a movable 90 part of the controlling-switch when moved in one direction, means for automatically disestablishing said engagement upon reaching a given point in said movement, a connection between said device and the spring-switch, 95 and a separate device attached to said connection and having operative engagement with said movable part of the controlling-switch when the latter moves in the opposite direction, substantially as described. 100

4. The combination with a motor-circuit and a controlling-switch *A* governing said circuit of a series-break switch *B* provided with an actuating-spring and an intermittent connection between said controlling-switch and 105 said series-break switch in both directions, whereby motion of controlling-switch *A* in one direction first closes series break *B* and then leaves it unaffected, and motion in the other direction instantly opens said series-break switch *B*, substantially as and for the 110 purposes set forth.

5. In combination with a motor-circuit and a controlling-switch adapted to vary the external resistance of the motor-circuit by coupling up the coils of the motor in varying orders and also to cut resistance in and out of said circuit, a line-switch connected with said controlling-switch intermittently in one direction of motion and continuously in the other 120 direction, substantially as and for the purposes set forth.

6. In combination with a motor-circuit and a controlling-switch a line-switch and intermittent connection between said two switches 125 whereby motion of said controlling-switch in either direction first operates said line-switch and then may be continued without affecting said line-switch, substantially as shown and described. 130

7. In combination with controlling-switch *A*, a series-break switch *B*, a connection be-

tween said switches, a ratchet-wheel upon said controlling-switch, a lug on said ratchet-wheel and a double pawl carried on the connection between said switches, substantially 5 as and for the purposes set forth.

8. In a controller for electric motors, circuit-changing and resistance-varying stationary and movable contacts in combination with an initially-acting switch and a controlling 10 connection actuated by the normal movement of said movable contacts in one direction to close said switch and by the opposite movement to open the same, the first-named position of said switch being maintained during 15 the variation of resistance in the circuit and the second position being maintained during a reverse movement of the resistance-varying contacts, as and for the purpose set forth.

9. In a controller for electric motors, a controller-drum and means for actuating the 20 same for effecting the circuit changes and resistance variations, in combination with an initially-acting switch and connections between said switch and drum whereby when 25 said drum is moved toward "on" position said switch is closed and maintained in closed position during the "on" movement of the drum, and when said drum is moved toward "off" position said switch is opened and maintained in open position during the "off" movement of the drum, as and for the purpose set forth.

10. The combination with a controller 30 adapted to change the circuit connections and 35 vary the circuit resistance, of an initially-acting switch arranged to make or break the

main circuit in advance of the action of said controller when actuated in one direction or the other, and connections between said controller and switch whereby when the former 40 is actuated in either direction the latter is moved into coöperative position and maintained in that position during the completion of the movement of the controller, as and for the purpose set forth.

11. In a controller for electric motors, the combination with stationary contacts, a co-operating contact-bearing drum and actuating means therefor, of a circuit making and breaking switch, a controlling mechanism intermediate said switch and said drum-actuating means, which insures the opening of the circuit by a backward movement of the drum-actuating means from any point, and the closing of the same only when the drum is in position to include the necessary resistance in 55 circuit, as and for the purpose set forth.

12. In a controller for electric motors, the combination with stationary contacts, a co-operating contact-bearing drum, and an actuating device therefor, of a circuit making and breaking switch, an opening and closing mechanism therefor, actuated or controlled by a backward movement of the drum-actuating device from any point to open said switch, 60 and by a forward movement to close the same only when the drum is in its initial or "off" position, as and for the purpose set forth.
